CONTROL DEVICE

John D. Bolesky, Attleboro, Mass., assignor to
 Metals & Controls Corporation, Attleboro,
 Mass., a corporation of Massachusetts

Original application April 5, 1939, Serial No.
 266,078. Divided and this application January
 2, 1943, Serial No. 471,141

7 Claims. (Cl. 200—155)

This invention relates to control devices, and, with regard to certain more specific features, to electric snap switches and valves, for example, of the manually actuated type.

This application is a division of my copending application Serial No. 266,078, filed April 5, 1939, now Patent No. 2,327,836, granted Aug. 24, 1943.

Among the several objects of the invention may be noted the provision of a control device, such as an electric switch, which can be used both to connect and disconnect a motor or other electrical device in whose circuit it is connected; the provision of an electric switch of the class described which is so constructed as to include novel means for preventing the formation of contact-destroying arcs; and the provision of control devices of the class described which are relatively economical to make, and safe in operation. Other objects will be in part obvious and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which is illustrated one of various possible embodiments of the invention,

Fig. 1 is a top plan view of a switch embodying the present invention;

Fig. 2 is a vertical cross section taken substantially along line 2—2 of Fig. 1;

Fig. 3 is a cross section taken substantially along line 3—3 of Fig. 2; and

Fig. 4 is a section along line 4—4 of Fig. 3.

Similar reference characters indicate corresponding parts throughout the several views of the drawing.

While the present invention comprehends control devices of many types, the embodiment to which the present application primarily relates is an electric switch actuatable manually.

Figures 1 through 4 show a practical switch embodiment of the invention following the general principles set forth in my copending application, Serial No. 266,078, referred to above.

Referring to Figures 1 through 4, numeral 30 indicates a base for the switch of cup-like construction, comprising a bottom portion 31 and an upstanding, generally cylindrical wall 32. Projecting out of the top of the cup-shaped base 30 is a generally cylindrical control knob 33, the particular construction of which will be given in greater detail hereinafter. Both the base 30

and the knob 33 are preferably made of an electrical insulating material, such as molded Bakelite, porcelain, etc. Base 30 is preferably provided with external mounting ears 29.

5 Mounted centrally in the bottom 31 of the base 30 is a threaded post 34, which has a polygonal head 35 for adjusting purposes. A lock nut 36 secures the relative adjustment of the post 34 in the bottom 31. On the other side of the bottom 10 31, the post 34 is extended into knob 33 as an unthreaded cylindrical portion 37 of reduced diameter.

Extending through the bottom 31 of the base 30 are two electrical terminal pieces 38 and 39. 15 Terminal pieces 38 and 39, it will be seen, are diametrically opposite each other.

The terminal pieces 38 and 39 comprise sheet metal stampings which are force-fitted into the bottom 31 of base 30, affording internal contact 20 faces 41 and 42, respectively, and external loops 44 and 45, respectively, to which external connections may be made as by soldering. The particular construction of the terminal pieces 38 and 39 is immaterial to the present invention, 25 and hence need not be described at length herein.

The internal wall of the cylindrical portion 32 of the base 30 is provided with diametrically opposite bayonet-type notches 49, extending 30 through, say, about 60° of arc. The notches 49 have, at one diametrically opposite end of each, relatively deeper portions 50, extending through about, say, 25° of arc, and bottoming on the inner surface of the bottom 31. The notches 49 35 also have relatively shallower diametrically opposite portions 51, which terminate downwardly as flat ledges or platforms 52.

Mounted on the reduced diameter portion 37 40 of post 34, on the shoulder afforded by the termination of the threaded portion of said post 34, is a peripherally grooved collar 53, into the groove of which relatively loosely fits the internal periphery of a concave monometallic spring disc 103 of the same general form as the thermostatic 45 disc 28 shown in Fig. 10 of my said application, Serial No. 266,078. The disc 103 is held in position in the groove 53 by a collar or nut 55, which clamps down on the collar 53. The collar 55 is force-fitted to the reduced diameter 50 portion 37 of post 34, so that it cannot rotate relative thereto. On the surface of disc 103 facing the bottom 31 are mounted, as by welding, in diametrically opposite positions, a pair of contact buttons 56 and 57, which are positioned at 55 suitable radial distances to engage contact plates

41 and 42 when the disc 103 is in the Fig. 1 position.

Referring now more particularly to Figures 2 and 3, it will be seen that the disc 103 is provided, at diametrically spaced points on its periphery, with a pair of upstanding ears 58. On each side of each ear 58 is a projection 59 extending outwardly from the periphery of the disc 103, but relieved slightly from said disc for a portion of its length remote from the ear 58 in order to be bent upwardly to form a sloping surface of an inclined-plane, camming character (see Fig. 4). The slope is opposite in direction for each projection of the pair on either side of each ear 58.

The disc 103, it will be understood, rotates 15 freely in the groove of collar 53, relative to the post 34.

Surmounting the collar 55 on the reduced diameter portion 37 of post 34 is a relatively long sleeve 64, the outer end of which is outwardly flanged as indicated at numeral 65. Preferably the sleeve 64 is a forced-fit on the post portion 37, so that it does not rotate relative thereto. Beyond the flange 65, reduced diameter portion 37 is preferably upset and headed over, as indicated at numeral 66.

Extending outwardly from the outer periphery of knob 33, at the inner end thereof, are diametrically opposite projections 70. Each projection 70 includes, in its under surface and at its outer edge, a notch 71 of sufficient width freely to receive the upstanding projection 58 on the periphery of disc 103. The notches 71 are of sufficient depth to accommodate said projections 58.

The projections 70 extend radially outwardly sufficiently far so that they fit only into the bayonet-type notches 49 in the base member 30. By abutting the ends of said bayonet notches 49, the said projections 70 limit the rotative movement of the knob 33 in the base 30.

As shown in Fig. 1, the outer face or end of the knob 33 is preferably provided with a position-indicating means, such as the arrow 33a.

The sloping character of the projections 59 makes it possible manually to rotate the knob 33, and with it the disc 103, in a counterclockwise manner. The sloping faces of these projections 59, ride up on the ledges 52 under such manual actuation of the knob 33.

This switch operates as a simple electrical make-and-break switch by manually rotating the knob 33 with its projections 70 consequently moving to and fro in bayonet-type slots 49. In one position movable contacts 56 and 57 rest on fixed contacts 41 and 42 to complete (or make) connections between terminals 38 and 39. In the other position movable contacts 56 and 57 are angularly displaced from fixed contacts 41 and 42 to disconnect (or break) connections between terminals 38 and 39. The spring disc 103 never snaps to opposite curvature, but its inherent resiliency makes for firm contact pressure when the switch is closed, and positive separation when the switch is open.

In view of the above, it will be seen that the several objects of the invention are achieved and other advantageous results attained.

As many changes could be made in carrying out the above constructions without departing from the scope of the invention, it is intended that all matter contained in the above description or shown in the accompanying drawing shall be interpreted as illustrative and not in a limiting sense.

I claim:

1. In a control device, a base member, a post mounted thereon, a spring member comprising a dished resilient monometallic disc mounted on said post substantially parallel to said base and resiliently bearing thereagainst and rotatable with respect to said base in a plane substantially parallel to said base, said spring having at least one peripheral projection of cam shape, means extending upwardly from said base and engaging both sides of said projection to define one angular position of said spring, said last-named means extending circumferentially in one direction as a ledge on to which said projection rides against the normal tension of said spring to define a second angular position of the spring, and control means determined as to condition by the relative angular disposition of said spring and said base.

2. In a control device, a base member, a post mounted thereon, a spring member comprising a dished resilient monometallic plate mounted on said post substantially parallel to said base and resiliently bearing thereagainst and rotatable with respect to said base in a plane substantially parallel to said base, said spring having at least one peripheral projection of cam shape, means extending upwardly from said base and engaging both sides of said projection to define one angular position of said spring, said last-named means extending circumferentially in one direction as a ledge on to which said projection rides against the normal tension of said spring to define a second angular position of the spring, and control means determined as to condition by the relative angular disposition of said spring and said base.

3. In a control device, a base member, a post mounted thereon, a spring member comprising a dished resilient monometallic disc mounted on said post substantially parallel to said base and resiliently bearing thereagainst and rotatable with respect to said base in a plane substantially parallel to said base, said spring having at least one peripheral projection of cam shape, means extending upwardly from said base and engaging both sides of said projection to define one angular position of said spring, said last-named means extending circumferentially in one direction as a ledge on to which said projection rides against the normal tension of said spring to define a second angular position of the spring, and control means determined as to condition by the relative angular disposition of said spring and said base.

4. In a control device, a base member, a post mounted thereon, a spring member comprising a dished resilient monometallic plate mounted on said post substantially parallel to said base and resiliently bearing thereagainst and rotatable with respect to said base in a plane substantially parallel to said base, said spring having at least one peripheral projection of cam shape, means extending upwardly from said base and engaging both sides of said projection to define one angular position of said spring, said last-named means extending circumferentially in one direction as a ledge on to which said projection rides against the normal tension of said spring to define a second angular position of the spring, and control means determined as to condition by the relative angular disposition of said spring and said base.

5. In a control device, a base member, a post mounted thereon, a spring member comprising a dished resilient monometallic plate mounted on said post substantially parallel to said base and resiliently bearing thereagainst and rotatable with respect to said base in a plane substantially parallel to said base, said spring having at least one peripheral projection of cam shape, means extending upwardly from said base and engaging both sides of said projection to define one angular position of said spring, said last-named means extending circumferentially in one direction as a ledge onto which said projection rides against the normal tension of said spring to de-

fine a second angular position of the spring, and control means determined as to condition by the relative angular disposition of said spring and said base, manually operable handle means mounted on said post, and means interconnecting said handle means and said spring for co-extensive rotary movement, said interconnecting means including an upstanding projection on said spring which extends into a suitable recess in said handle means.

5. A control device comprising a base member, a post mounted thereon, a spring member comprising a resilient monometallic disc mounted on said post and resiliently bearing against said base, said disc being mounted rotatable with respect to said base, said spring having at least one peripheral projection of cam shape, and means extending from said base and engaging said projection to define a plurality of angular positions of said spring.

6. A control device comprising a base member, a post mounted thereon, a spring member comprising a resilient monometallic disc mount-

ed on said post and resiliently bearing against said base, said disc being mounted rotatable with respect to said base, said spring having at least one peripheral projection of cam shape, means extending from said base and engaging said projection to define a plurality of angular positions of said spring, and a movable contact mounted on said disc and resiliently pressed against said base by said disc.

10. 7. A control device comprising a base member, a post mounted thereon, a spring member comprising a resilient monometallic disc mounted on said post and resiliently bearing against said base, said disc being mounted rotatable with respect to said base, said spring having at least one peripheral projection of cam shape, means extending from said base and engaging said projection to define a plurality of angular positions of said spring, and a movable contact mounted on said disc and resiliently pressed against said base by said disc, said disc being concave on its contact side.

JOHN D. BOLESKY.
